Primary Examiner — Elizabeth J Oswecki(74) *Attorney, Agent, or Firm* — Pearl Cohen Zedek Latzer Baratz LLP(57) **CLAIM**

The ornamental design for a connection module, as shown and described.

DESCRIPTION

FIG. 1 is a top, front, right side perspective view of a connection module showing our new design;

FIG. 2 is a bottom plan view thereof;

FIG. 3 is a top plan view thereof;

FIG. 4 is a front elevation view thereof;

FIG. 5 is a back elevation view thereof;

FIG. 6 is a left side elevation view thereof;

FIG. 7 is a right side elevation view thereof; and,

FIG. 8 is a bottom, back, right left side perspective view thereof.

The broken lines show portions of the connection module that form no part of the claimed design.

1 Claim, 5 Drawing Sheets(56)
